PRECISION HAMMER

Alfred A. Bamberger, Flushing, N. Y., assignor to
 Speedo Manufacturing Co., Inc., New York,
 N. Y.

Application April 22, 1947, Serial No. 743,086

3 Claims. (Cl. 125—33)

1

This invention relates to a precision hammer. More particularly it is concerned with hammers of the type in which the head is reciprocated by the repeated impact of a cam operated member driven by a flexible shaft.

An object of this invention is to provide a hammer of the character described in which the head member of the device receives on a rear portion thereof, the repeated impact of a cam actuated slideable member which is urged toward said head member by a spring member together with improved rotary adjusting means mounted on the device for regulating the tension of said spring member.

A further object of this invention is to provide in a device of the character described a plunger casing together with a plunger disposed for reciprocating movement therein, together with spring means for urging the plunger in one direction and a rotatable, non-slideable sleeve on the plunger casing which engages a slideable member within the plunger casing and in abutting contact with said spring member whereby rotation of said sleeve imparts longitudinal movement to the slideable member and thereby determines the biasing action of the spring member with respect to the plunger.

Still another object of this invention is to provide a hammer comprising a plunger casing having a reciprocating hammer head extending from one end thereof and having the other end thereof provided with a bearing nut through which passes a rotatable, non-slideable shaft for imparting reciprocating motion to a plunger member disposed within the plunger casing and coaxial with the hammer head, together with a sleeve nut threaded externally at either end thereof and received on one end in the bearing nut, the other end being adapted to receive various types of couplings for interconnecting flexible shafts to said rotatable, non-slideable shaft.

Still a further object of this invention, is to provide a compact and durable device of the character described which shall be relatively inexpensive to manufacture, easy to manipulate, which shall be smooth and positive in operation, and yet practical and efficient to a high degree in use.

Other objects of this invention will in part be obvious and part hereinafter pointed out.

The invention accordingly consists in the features of construction, combinations of elements, and arrangement of parts which will be exemplified in the construction hereinafter described,

2

and of which the scope of application will be indicated in the following claims.

Fig. 1 is an axial cross sectional view of the device embodying the invention;

5 Fig. 2 is a cross sectional view taken on the line 2—2 of Fig. 1;

Fig. 3 is a cross sectional view taken on the line 3—3 of Fig. 1;

10 Fig. 4 is a cross sectional view taken on the line 4—4 of Fig. 1;

Fig. 5 is an elevational view of the connector portion of the device embodying the invention;

15 Fig. 6 is an axial sectional view of a flexible shaft connector assembly portion of the device embodying the invention and illustrating a modification thereof;

Fig. 7 is an axial sectional view similar to that shown in Fig. 6 and illustrating a modification thereof;

20 Fig. 8 is an axial sectional view similar to that shown in Fig. 6 and illustrating another modification thereof; and

Fig. 9 is a cross sectional view taken on the line 9—9 of Fig. 1.

25 Referring now in detail to the drawing, 10 designates a device of the character described. The same comprises a tubular casing 11 having an internally threaded portion 12 at the forward end thereof and having screwed therein a tapered housing 13 coaxial with the casing. The hammer housing 13 comprises a base portion 14 of reduced diameter which is externally threaded and engages the threaded portion 12 of the casing 11. The housing 13 is formed with 30 an axial bore 15 from which extends rearwardly, a communicating recess 16 of enlarged diameter. A tool holder 17 is mounted for slideable movement within the bore 15. The tool holder 17 comprises an enlarged rear portion 18 which is slidably received in the recess 16 and comprises 35 an end wall 18a which projects outwardly of the recess 16. The enlarged rear portion 18 of the tool holder is formed with a transverse opening 19 in which is received a pin 20, the outer end portions of which projects on either side of the enlarged portion 18. The projecting portions of the pin 20 are received within aligned openings 21 formed in opposite sides of the base portion 14 of the housing 13. The openings 21 are 40 of a diameter permitting limited longitudinal movement of the tool holder 17 in either direction. A coil spring 22 is mounted on a rear portion of the tool holder 17 and is disposed in the recess 16 between the forward end of the 45 recess and the enlarged rear portion 18 of the

50

tool holder. The spring 22 normally urges the tool holder to its rearmost position, as determined by the pin 20. The forward end of the tool holder 17 is formed with an internally threaded axial recess or socket 23 which receives an externally threaded rod or point 24.

A plunger or hammer 25 coaxial with the tool holder 17, is mounted for slidable movement within the plunger housing 11. The plunger 25 comprises a front wall 26 disposed opposite the wall 18a of the tool holder. The plunger 25 is formed with a longitudinal guide slot 26a on a wall thereof, in which projects a guide member 27 secured to the plunger housing 11. The plunger 25 is further formed with an axial recess 28 opening on the rear end thereof and formed with screw threads 29. Disposed with in the recess 28 of the plunger is a cam member 30 which comprises a helically cut rearward face 31. The cam 30 is further formed with an internally threaded axial opening 32 into which is screwed the threaded end portion of a rotatable, non-slidable shaft 33. A cam follower 34 is rotatably and slidably disposed on the shaft 33 and comprises a helically cut forward face 35 which is complementary to the face 31 of the cam 30 and a flanged portion 36 on the rear end thereof. The cam follower 34 is formed with an externally threaded portion 37 adjacent the flange 36, which is received in the threaded portion 29 of the plunger 25, the flange 36 bearing against the rear end of the plunger 25.

The plunger housing 11 further comprises a rearwardly extending cylindrical wall 38 of reduced external diameter forming a forward shoulder portion 38a. The wall 38 of the housing 11 is formed with a pair of longitudinally extending, aligned slots 39 on opposite wall surfaces thereof. The wall 38 further comprises an internally threaded portion 40 on the rear portion thereof. A bearing nut 41 is screwed into the wall 38. The bearing nut 41 comprises a cylindrical wall 42 comprising an externally threaded outer surface 43 which engages the threaded portion 40 of the wall 38. The nut 41 further comprises an outwardly turned flange 44 at the rear end thereof which abuts the end of the wall 38. The bearing nut 41 also comprises an inwardly turned flange bearing portion 45 formed with a through opening 45a in which is journalled a rear portion of the rotatable, non-slidable shaft 33. The inner surface of the wall 42 of the nut 41 is internally threaded to receive a sleeve nut 46 formed with a through axial opening 46a for receiving the shaft 33. The sleeve nut 46 comprises an annular wall 47 abutting the flange 44 of the bearing nut 41 and from one side of which extends an externally threaded sleeve portion 48 which is screwed into the internally threaded portion of the bearing nut 41. An externally threaded sleeve portion 49 extends rearwardly from the wall 47. The shaft 33 comprises a collar 50 secured thereon. The collar 50 is disposed with its forward side in contact with the flanged portion 45 of the bearing nut 41 and sleeve portion 48 of the sleeve nut 46 bearing against the rear side of the collar 50 thereby preventing longitudinal movement of the shaft 33.

A rotatable, adjusting sleeve 51, having an internally threaded surface 52 is disposed over the wall 38 between the shoulder 38a and the flange 44, substantially flush with the outer surface of the plunger housing 11. The threaded surface 52 terminates short of the end of the sleeve 51. An adjusting nut 53 is slidably and non-rotatably

mounted on the shaft 3. The nut 53 comprises a central opening 54 through which the shaft 33 passes and from which extends an enlarged recess 55. Wing portions 56 extend radially from opposite sides of the recessed portion 55 and comprises threaded outer surfaces 57. The outer end portions of the wings 56 are disposed in the slots 39 in the wall 38, the threaded surfaces 57 projecting above the outer surface of the wall 38 and engaging the threaded surface 52 of the adjusting sleeve 51. A coil spring 57a is mounted on the shaft 33 bearing disposed between the flange 36 and the recess 55 in the collar 53. A clamping ring 58 is disposed between the unthreaded inner surface of the adjusting sleeve 51 and the outer surface of the wall 38.

The shaft 33 extends rearwardly through the sleeve nut 46, projecting beyond the sleeve portion 49 thereof. A threaded axial recess 59 is formed in the rear end portion of the shaft 33 and receives therein a coupling member 60. The coupling member 60 comprises a threaded forward end portion 61 which is screwed into the threaded recess 59 of the shaft 33. The rear end of the coupling is formed with an axial bore 62. A longitudinal slot 63 formed in member 60 communicates with the bore 62.

A sleeve 64 is concentrically mounted with respect to the coupling member 60. The sleeve 64 comprises an internally threaded forward end portion 65 which is screwed on the externally threaded flange 49. Extending from the rear end of the sleeve 64 is an enlarged annular rear end portion 66. The wall of the annular portion 66 is formed with a recessed through opening 67 in which is seated a ball 68. The ball 68 is of a diameter such that it projects slightly beyond the outer and inner surfaces of the annular portion 66. A split spring sleeve 69 is disposed about the outer surface of the annular portion 66, and is formed with a transverse through opening 70 of a lesser diameter than that of the ball 68. The sleeve 66 overlies the outer wall of the annular portion 66 with the upper surface of the ball 68 received in the opening 70. The sleeve 64 receives the end portion of a flexible rotary shaft assembly 70a. The assembly 70a comprises a cylindrical head member 71 which is formed with an annular groove 72 on the circumference thereof. The member 71 is formed with an axial through opening 73 in which is received the rotary flexible shaft 74. The end portion of the shaft 73 comprises an upstanding rib 75. The end of shaft 74 is received in the axial bore 62 with the rib 75 engaged in the slot 63.

In using the device 10, the assembly 70a is connected to the sleeve 64 by inserting the member 71 in the annular portion 66 and moving it forwardly until the ball 68 engages the groove 72 in the member 71. The split sleeve 69 will maintain the ball 68 in this position. The end of the shaft 74 engages the coupling member 60 attached to the end of the shaft 33. The shaft 33 being rotated by the rotating flexible shaft 74, imparts rotary movement to the cam member 30 fixed thereto and disposed within the plunger 25. As the cam 30 rotates, its helically cut face 31, which is opposed to the helically cut face 35 on the cam follower 34, will progressively move the cam follower inwardly against the biasing action of the spring 57a. When the toe of the cam follower 34 just passes the toe of the cam 30, the cam follower will be instantly urged outwardly by the coil spring 57a. Since the plunger 25 is screwed on the cam follower 34, its axial move-

ment will follow the movement of the follower. Accordingly, the outward movement of the cam follower will produce a similar outward movement of the plunger 25. The front wall 25 of the moving plunger will produce a sudden impact on the rear wall 18a of the tool holder 17, moving the tool holder 17 outwardly against the action of the spring 22. The movement of the tool holder 17 will be limited by the pin 20. The spring 22 will restore the tool holder 17 to the normal rearward position immediately after the retraction of the plunger 25. Upon continued rotary movement of the shaft, the cam 30 will repeat its action with respect to the cam follower and the associated plunger. As a result the tool holder 17 will have a staccato, reciprocating action. The hammer 17 is provided with a removable pin 24 which may be replaced by other pins selected for the particular type of work to be done by the device.

The action of the tool holder 17 may be regulated as to its force of impact. By rotating the sleeve 51, the nut 53 is moved longitudinally within the slots 38 in the wall 38. The position of the collar 53 in turn determines the biasing action of the spring 57a. It is thus possible to regulate the action of the tool holder by simply rotating the sleeve 51 in either direction to produce a desired type of impact.

The device 10 may be interconnected to various types of flexible shafts by modified coupling constructions. In Fig. 6 is shown a modified form of shaft coupling. The same comprises a member 76 formed with an axial through opening 77 and a communicating longitudinal slot 78 at one end thereof. The other end of the member 76 is internally threaded to receive the threaded end 79 of a coupling member 80. The other end of the coupling member 80 also comprises a threaded portion 80a on its opposite end which is engaged in the threaded bore portion 59 of the shaft 33. The shaft 74 having a rib 75, is connected to the member 76 in the manner previously described. A concentric sleeve 81 having an internally threaded end portion 82 is screwed on to the threaded flange 49 of the sleeve nut 46.

The coupling shown in Fig. 7 is similar to that shown in Fig. 6 except that it is modified to receive a flexible shaft 74a formed with a threaded axial recess 82 which is engaged by the threaded portion 79 of the coupling 80.

In Fig. 8 is shown a coupling assembly wherein the shaft 33 has a threaded connector rod 83 screwed into the threaded recess 59. A tubular casing 84 comprising an internally threaded end portion 85 is screwed on to the threaded flange 49 of the sleeve nut 46. The opposite end of the casing 84 is formed with a through opening 86. This form of coupling is adapted to receive a flexible shaft having a chuck portion which is engageable with the projecting end of the connector rod 83. A conventional fitting on the flexible shaft snaps into the opening 86 on the casing 84 thereby retaining the flexible shaft in engaging relationship with the shaft 33 through the rod 83.

It will thus be seen that there is provided a device in which the several objects of this invention are achieved, and which is well adapted to meet the conditions of practical use.

As various possible embodiments might be made of the above invention, and as various changes might be made in the embodiment above set forth or shown in the accompanying drawing

is to be interpreted as illustrative and not in a limiting sense.

Having thus described my invention I claim as new and desire to secure by Letters Patent:

1. An instrument comprising a casing having an internally threaded front end portion, a housing in front of said casing and having its rear portion screwed into the front end of the casing, said housing being formed with a longitudinal bore having its rear portion enlarged and forming a recess, the rear portion of the wall of said recess being formed with oppositely disposed openings, a tool carrier slideable longitudinally through the bore and having a head at its rear end fitting snugly in said recess and formed with a transverse opening aligned with the opposed openings of the housing, a spring in said recess coiled about said tool holder and acting upon the head to urge the tool holder rearwardly, a pin passing through the opening in the head with end portions projecting therefrom and loosely fitting into the opposed openings of the housing and limiting the longitudinal movement of said tool holder, a plunger slideable longitudinally in said casing back of said tool holder and formed with a pocket leading from its rear end, a rotatable shaft extending longitudinally in said casing axially thereof with its front end extending into said pocket, a cam surrounding the front end of said shaft and turning therewith in the pocket, a bushing arranged in said pocket and loosely surrounding said shaft and having its front end engaged by said cam for intermittently shifting the plunger rearwardly during the rotation of the shaft, a collar surrounding said shaft and secured in said casing and spaced rearwardly from said plunger, a spring in said casing surrounding said shaft between the collar and the plunger and serving to drive the plunger forwardly into striking contact with the tool holder between rearward movements of the plunger by the action of said cam, and means for connecting the rear end of the shaft with a rotary drive shaft.

2. An instrument comprising a cylindrical casing open at its front end and also at its rear end, a housing extending from the front end of the casing and having its rear portion removably connected with the casing, said housing being formed with a longitudinal bore having its rear portion enlarged and forming a recess, said recess having opposed wall portions formed with openings, a tool holder slideable longitudinally in said bore and having a head at its rear end slideable longitudinally in said recess and carrying a transverse pin having ends projecting from the head and loosely fitting in the openings to limit the longitudinal movement of the tool holder, a spring urging said tool holder rearwardly, a plunger slideable longitudinally in said casing and held against rotation, said plunger being formed with a pocket leading from its rear end, a bushing secured in said pocket and spaced from the front end thereof, a rotatable shaft extending longitudinally in said casing and having its front end passing through said housing and carrying a cam acting upon the front end of the bushing to intermittently shift the plunger rearwardly during the rotation of the shaft, a spring urging said plunger forwardly for striking engagement with the head of the tool holder between rearward movements of the plunger by said cam, and a removable closure for the rear end of the casing rotatably mounting said shaft.

3. An instrument comprising a cylindrical casing open at its front and rear ends and having

an intermediate portion inwardly thickened and forming a bore, a housing secured in the forward end of said casing and projecting forwardly therefrom, a tool holder slideable longitudinally through said housing and having a head at its rear end, a spring urging said tool holder rearwardly, a pin limiting the longitudinal movement of the tool holder, a plunger slideable longitudinally in the bore of said casing and held against rotation, said plunger being formed with a pocket leading from its rear end and internally threaded from its rear end for a portion of its length, a bushing screwed into said pocket and having an annular flange about its rear end abutting the rear end of the plunger, the front end of said bushing being spaced from the front end of the pocket and formed with a circumferentially extending cam surface, a rotatable shaft extending longitudinally in said casing with its front end portion passing through said bushing and carrying a cam disposed between the front ends of the bushing and the pocket and coacting with the cam surface of the bushing for intermittently shifting the plunger rearwardly during the rotation of the shaft, a collar surrounding said shaft and secured in the rear end portion of said

15 casing, a spring surrounding said shaft and bearing against said collar and the rear flange of the bushing for shifting the plunger forwardly into striking contact with the head of the tool holder
5 between rearward movements of the cam during the rotation of the shaft, a closure for the rear end of the casing surrounding and rotatably supporting the shaft and for holding the shaft against longitudinal movement, and a coupling
10 for connecting the rear end of the shaft with a rotary drive shaft.

ALFRED A. BAMBERGER.
